UNITED STATES PATENT OFFICE.

EDWARD E. WHITMORE, OF CHICAGO, ILLINOIS, ASSIGNOR TO THE CURTAIN SUPPLY COMPANY, OF CHICAGO, ILLINOIS, A CORPORATION OF ILLINOIS.

CAR-DIAPHRAGM.

1,221,399.

Specification of Letters Patent.

Patented Apr. 3, 1917.

Application filed January 11, 1917. Serial No. 141,748.

To all whom it may concern:

Be it known that I, EDWARD E. WHITMORE, a citizen of the United States, residing at Chicago, in the county of Cook and State of Illinois, have invented certain new and useful Improvements in Car-Diaphragms, of which the following is a specification.

The invention has for its special object the provision of an improved metallic diaphragm for railway cars especially adapted for efficient and economical application to baggage and postal cars.

Among other constructional differences characterizing cars of this type, is the disposition of the end I-beams of the car which flank the end door way, exterior of the car, the same not being finished in but having their flanges exposed.

20 In the application of telescopic metallic diaphragms to railway cars as now practiced, considerable expense is involved in providing for the attachment of the side members to the car end, pockets or other housings being formed in the car end for the reception of the telescoping member adjacent the car, or a special diaphragm side wall member being riveted or otherwise secured to the I-beams or door posts.

30 According to the present invention, advantage is taken of the characteristic postal car construction, to utilize the I-beams of the car frame as the inner diaphragm side wall members, the outer flange of the beams serving to form the interlocking element for coöperation with a similar flange formed on the outer side wall member carried by the face plate. This greatly cheapens the cost of production, reduces the weight by approximately one-half, and facilitates the application of metallic vestibule diaphragms to both new and old cars of this type.

40 In order that the invention may be readily understood by those skilled in the art, a preferred embodiment of the same is set forth in the accompanying drawing and in the following detailed description based thereon. As the invention may be embodied in other and varied constructional forms, the drawing and description are to be taken in an illustrative and not in an unnecessarily limiting sense. In the drawing—

Figure 1 is an end elevation of a postal car equipped with the invention;

Fig. 2 is a fragmentary longitudinal section taken on the line 2—2 of Fig. 1;

Fig. 3 is a fragmentary horizontal section taken on the line 3—3 of Fig. 1; and

Fig. 4 is a similar section taken on the line 4—4 of Fig. 1.

As illustrated, the car end is indicated at 11, the upper end sheathing at 12, the platform at 13, the door posts at 14 and the I-beams of the frame at 15. This is the usual construction in cars of the mail or baggage type.

The face plate 16 is carried by the buffer beam and controlled by spring pressed buffer stems as is usual, the same not being herein illustrated; the upper portion of the 70 face plate being resiliently controlled by means of the spring 17 bearing in its medial portion against the face plate and at its two ends against the I-beams 15.

A metallic diaphragm supplemental to 75 and arranged for attachment to a car of this type comprises a box-like structure having the side wall members 18—18 and cover member 19, preferably of apex shape, rigidly connected to and forming in effect an 80 integral structure with the side walls 18. The side walls and cover are at their outer edges flanged as indicated at 18^a and 19^a respectively, for attachment to the face plate as indicated. The inner edges of the side 85 wall members and cover member are outwardly flanged as indicated at 18^b and 19^b respectively, the former for engagement with the flanges 15^a of the I-beams 15 and the latter to serve as a baffle plate to obstruct the entrance of the elements between the said flange 19^b and the end finish sheathing 12 of the car. The space between the I-beams 15 may be cut off from the interior 90 of the car by finish plates 20 and 21, the latter arranged above the flange 19^b of the cover diaphragm member.

It will readily be seen that according to the present invention it is a very easy and comparatively inexpensive proceeding to attach to a mail or baggage car the necessary elements for equipping the same with a metallic telescoping diaphragm, the attachment consisting in substance of a box or inverted U comprising the side wall members 18 and cover member 19, the inner flanges of the same interlocked with the outer flange of the I-beams and the outer flanges secured to

the existent face plate of the vestibule. The weight is much less than that of metallic diaphragms of present construction, and the time during which the car must be withdrawn from service in order to have the attachment made is practically negligible.

It will be understood that in some cases the I-beams may not be exposed in the sense of being externally visible, and yet

- 10 may be exposed in the sense of being available for coöperation, in the manner hereinbefore indicated, with the side wall members of the diaphragm, thus enabling the utilization of the I-beams as elements of the diaphragm construction; wherefore the claims are to be thus liberally construed except as otherwise specifically limited in terms.

I claim:

1. In a metallic vestibule diaphragm for cars of the postal type having exposed end I-beams, a pair of side wall members and a cover member connected together to form an inverted U construction, the side wall members and cover member provided along their outer margins with means of attachment to the face plate, the side wall members provided along their inner margins with a flange for coöperation with the I-beams of the car frame.
2. In a metallic vestibule diaphragm for cars of the postal type having exposed end I-beams, a pair of side wall members and a cover member rigidly connected together to form an inverted U construction, the side wall members and cover members provided along their outer margins with flanges for attachment to the face plate, the side wall members provided along their inner margins with flanges for coöperation with the flanges of the I-beam.
3. In a metallic vestibule diaphragm for cars of the postal type having exposed end I-beams, a pair of side wall members and a cover member connected together to form an inverted U-construction, the side wall members and cover member provided along their outer margins with a flange for attachment to the face plate, the side wall members provided along their inner margins with an outwardly turned flange for interlocking coöperation with the I-beams of the car frames, and the cover member having an outwardly turned flange for coöperation with upper end sheathing of the car as a baffle plate to exclude the elements.
4. In a metallic vestibule diaphragm for cars of the postal type having exposed end I-beams, a pair of side wall members and a cover member connected together to form an inverted U-construction, the side wall members and cover members provided along their outer margins with a flange for attachment to the face plate, the side wall members provided along their inner margins with an outwardly turned flange for inter-

locking coöperation with the I-beam of the car frames, and the cover member having an outwardly turned flange for coöperation with upper end sheathing of the car as a baffle plate to exclude the elements, the inner flanges of the side and cover members arranged to normally operate out of contact with the flanges of the I-beams and sheathing respectively.

5. In a metallic vestibule diaphragm for cars of the postal type, the combination with the structural end I-beams of the car extending beyond the car end and exposed for a vertical distance corresponding substantially to the height of the vestibule, and the upper end sheathing covering the I-beams above the height of the vestibule, of a pair of side wall members and a cover member connected together to form an inverted U-construction, the side wall members and cover member provided along their outer margin with means of attachment to the face plate, the side wall members provided along their inner margins with a flange for interlocking coöperation with the I-beams of the car frame, and the cover member having an outwardly turned flange for coöperation with the upper end sheathing of the car as a baffle plate to exclude the elements.

6. In a metallic vestibule diaphragm for cars of the postal type, the combination with the structural end I-beams of the car extending beyond the car end and exposed for a vertical distance corresponding substantially to the height of the vestibule, and the upper end sheathing covering the I-beams above the height of the vestibule, of a pair of side wall members and a cover member rigidly connected together to form an inverted U-construction, the side wall members and cover member provided along their outer margins with means of attachment to the face plate, the side wall members provided along their inner margins with an outwardly turned flange for interlocking coöperation with the inwardly extending flanges of the I-beams, and the cover member having an outwardly turned flange for coöperation with the upper end sheathing as a baffle plate to exclude the elements.

7. In a metallic vestibule diaphragm for cars of the postal type, the combination with the structural end I-beams of the car extending beyond the car end and exposed for a vertical distance corresponding substantially to the height of the vestibule, and the upper end sheathing covering the I-beams above the height of the vestibule, of a pair of side wall members and a cover member rigidly connected together to form an inverted U-construction, the side wall members and cover member provided along their outer margins with means of attachment to the face plate, the side wall mem-

bers provided along their inner margins with an outwardly turned flange for interlocking coöperation with the inwardly extending flanges of the I-beams, and the cover member having an outwardly turned flange for coöperation with the upper end sheathing as a baffle plate to exclude the elements, the inner flanges of the side and cover members arranged to normally operate out of contact with the flanges of the I-beams and the sheathing respectively.

8. In a metallic vestibule diaphragm for cars having end I-beams, a pair of side wall members and a cover member bridging the space therebetween, the side wall members and cover member provided along their outer margins with means of attachment to the face plate, and the side wall members provided along their inner margins with a flange for coöperation with the flanges of the I-beams of the car frame.

9. In a metallic vestibule for cars having end I-beams flanking the door-way, side wall

and cover members inclosing the vestibule and carried by the face plate, the side wall members provided along their inner margins with a flange for telescopic coöperation with the flanges of the said I-beams.

10. In a metallic vestibule diaphragm for cars having end I-beams, a pair of side wall members and a cover member bridging the space therebetween, the side wall members and the cover member provided along their outer margin with means of attachment to the face plate, and the side wall members arranged for telescopic coöperation of their inner margin with the said I-beams of the car.

In testimony whereof I have hereunto signed my name in the presence of two subscribing witnesses.

EDWARD E. WHITMORE.
